UNITED STATES PATENT OFFICE.

HENRY A. WISE WOOD, OF NEW YORK, N. Y., AND CONRAD NORDFORS, OF JERSEY CITY HEIGHTS, NEW JERSEY, ASSIGNEES, BY MESNE ASSIGNMENTS, TO WOOD NEWS-PAPER MACHINERY CORPORATION, OF NEW YORK, N. Y., A CORPORATION OF VIRGINIA.

BRAKING MECHANISM FOR ROTARY PRESSES.

1,311,031.

Specification of Letters Patent.

Patented July 22, 1919.

Application filed January 17, 1914, Serial No. 812,725. Renewed December 26, 1918. Serial No. 268,421.

To all whom it may concern:

Be it known that we, HENRY A. WISE WOOD and CONRAD NORDFORS, citizens of the United States, said Wood residing at New York, in the county of New York and State of New York, and said Nordfors residing at Jersey City Heights, county of Hudson, and State of New Jersey, have invented a new and useful Braking Mechanism for Rotary Presses, of which the following is a specification.

This invention relates to a printing press, being particularly applicable to the multiple deck type of rotary web presses.

The principal objects of the invention are to provide a quickly acting and simply constructed braking mechanism which is capable of checking simultaneously all the couples of a multiple deck press so as to avoid the difficulties ordinarily encountered in stopping web presses of this type; and to provide means for connecting the several impression cylinders with the power in such a way that any one of the cylinders can be disconnected simply and readily from the power without affecting the transmission of power to any of the other cylinders.

This invention constitutes an improvement over the application filed by Henry A. Wise Wood on a braking mechanism for presses, Serial No. 681,921, filed March 6, 1912.

Reference is to be had to the accompanying drawings, in which—

Figure 1 is a side elevation of a portion of a multiple deck rotary web printing press with a braking mechanism constructed in accordance with this invention:

Fig. 2 is a similar view on enlarged scale with some of the parts shown in section;

Fig. 3 is an end view of the mechanism shown in Fig. 2;

Fig. 4 is a central sectional view of the brake hub and connected parts enlarged;

Fig. 5 is a view similar to a portion of Fig. 4, on enlarged scale showing the cut-off pin; and

Fig. 6 is an end view of the mechanism shown in Fig. 5.

In the operation of web presses of the multiple deck type a serious difficulty has been encountered heretofore owing to the fact that when the press is stopped a brake

at the driving end of the machine is always applied. This results obviously in slowing up the machine from the power end so that the several decks, which are operated from the power through a series of gears, do not stop absolutely simultaneously but the one farthest from the power will get the effect of the brake later than the one nearest the power, due to the back lash. Owing to this fact, in part at least, the stopping of these presses has to be carried out very carefully in order to avoid the breaking of one or more of the webs and even the stripping of the gears. This necessitates the operation of the machine by a skilled mechanic and also results in the loss of some little time every time the machine is stopped.

This invention is designed for the purpose of overcoming these difficulties, permitting the machine to be operated by a man of less skill, and avoiding the web breaks and gear stripping which sometimes occurs even in the best operated plants.

The invention is shown as applied to a multiple deck rotary web printing press having a frame 10, a series of impression cylinders 11 and printing plate cylinders 12. In this type of press the power is transmitted through gearing 13 to a gear 14 rotatable on the same axis as one of the impression cylinders, that is, on the shaft 15. This gear meshes directly with another gear 14 preferably of the same size and on the same axis as another one of the impression cylinders. All the couples are operated in the same way by a series of these gears. Each of the impression cylinder shafts is provided with a gear 16 meshing with another gear on the printing cylinder shaft (not shown) and driving the printing cylinder 12 at the same surface speed.

In order that each of the gears 14 may be driven at all times when the machine is in operation, whether all the decks of the press are operating or not, these gears are shown as mounted loosely on the several impression cylinder shafts 15 by means, in the present instance, of a bushing 18. For the purpose of connecting each of these gears with its impression cylinder shaft 15, a hub 19 is keyed to each impression cylinder shaft 15 adjacent to the gear 14. One face of this

hub is provided with a socket 20 shown as having a lining 21. A plunger 22 is mounted in the face of the gear 14. The plunger 22 is spring-seated in the driving gear 14 and provided with a pin 23 adapted to engage a cam sleeve 24. The purpose of the pin and cam is to withdraw the plunger when it is desired to stop any of the cylinders from revolving. This is accomplished 10 by turning the pin one half a turn to the right. This causes the pin to mount the cam, incline thus drawing the plunger out of the hole or socket 20 of the brake hub 19.

The end of the pin or plunger 22 engaging the brake hub 19 is reduced in diameter to such an extent that should an overload be put on any of the cylinders it would break off and thus save any very serious breakage of the cylinder or other parts of the machine. 15

20 The pins or plungers 22 normally engage with the brake hubs 19.

This hub 19 has another function as it is used as a brake hub. A brake band 30 is provided on each brake hub, the two ends of 25 which are engaged by pins 31 with a lever 32. These levers are pivoted on studs 33 on a frame. The two pins 31 by which the ends of the brake band are connected with the lever, of course, are on opposite sides of the 30 pivot stud 33 and the swinging of the brake lever in one direction will cause the band to tighten.

It will be understood, of course, that the ends of the brake bands are provided with 35 adjusting rods 29 and nuts 28 for the purpose of taking up any wear on the brake bands.

These brake levers 32 are arranged in pairs for each two adjacent impression cylinders. 40 The free ends of two of the brake levers which project from opposite sides of their respective brake cylinders and extend in opposite directions therefrom, are connected by means of an air cylinder 34 which 45 is freely hung between two of the brake operating levers. The head of this cylinder is provided with an extension 36 which is attached to one of the levers by a pivot pin. Within the cylinder is a piston 37 which is 50 spring-seated by a spring 38 against the opposite end of the cylinder. This piston has a piston rod 39 which extends through that head of the cylinder and it is pivotally connected with the end of the other brake 55 operating lever. The piston, of course, is packed against leakage in any suitable manner and normally held in its extreme inward position by the action of the spring 38.

The head of the cylinder 35 is provided 60 with an opening or passage 39^a to which is connected a flexible pipe or hose 40. This in turn is connected with a main supply pipe 41. This pipe is connected with an air supply tank and is provided with the necessary 65 operating valve or valves 42. The main 41

is connected by several pipes 40 with an air cylinder 34 for each pair of impression cylinders.

In operation all of the plungers 22 of the impression cylinders which it is desired to 70 operate are allowed to move in by the cams to cause the end of each plunger to connect the gear with the brake hub. The power is transmitted through the several gears 14 to each of the impression cylinders so connected. If any of these cylinders are disconnected by the turning of the cams it will 75 make no difference in the transmission of power to the others.

When it is desired to stop the press the 80 usual stopping mechanism (not shown) is operated, and at the same time or preferably slightly afterward, the valve 42 is operated to admit air to the several cylinders 34. Each of the cylinders 34 is freely suspended 85 between two brake levers, the piston being connected with one and the rod with the other and the piston is spring-pressed. Therefore, it will be clear that this operation, although performed simultaneously on 90 all the impression cylinders, will take effect in such manner as to accommodate the conditions under which the press is being operated. In this way, the several printing couples are slowed down simultaneously but 95 independently when the press is stopped thus saving some time in providing for the same action on all the couples.

This also equalizes the stopping strains among the several couples so that none of 100 the webs are likely to be broken, and applies a gradual but equal amount of brake power to all the cylinders, allowing them to come to an even stop. As both the piston and cylinder are free members the whole braking 105 mechanism is equalized. The instant that either takes up the looseness it then becomes rigid and the other member is free to exert pressure therefrom in the opposite direction.

Although we have illustrated and described a preferred embodiment of the invention as applied only to one type of press, we are aware of the fact that many modifications can be made therein by any person skilled in the art without departing from 110 the scope of the invention as expressed in the claims. Therefore, we do not wish to be limited to all the details of construction, to the type of press herein shown and described, nor to the features which are also 115 shown in the above identified application, but what we do claim is:—

1. The combination with the two impression cylinders of a printing press deck, and means for driving them, of a brake hub on 125 each cylinder, a brake for each hub, a lever for operating each brake, and means supported by said levers for operating the two brakes simultaneously.

2. In a printing press, the combination 130

with a pair of cylinders and means for driving said cylinders, of a brake or retarding mechanism for each of said cylinders, and a single means comprising a movable cylinder 5 and piston, for operating said brake or retarding mechanisms simultaneously and oppositely to retard both cylinders.

3. The combination of a pair of hubs, a brake for each hub, a lever connected with 10 each of said brakes for operating it, a movable cylinder and piston, the piston being connected with one of said levers and the cylinder with the other, and means whereby fluid under pressure can be admitted into 15 the cylinder for moving the cylinder and piston apart to apply the brakes to the two hubs.

4. The combination with a multiple deck printing press, of means applicable to one 20 of the members of each printing couple for independently retarding the rotation thereof when the press is being stopped, and a cylinder and piston each connected to one retarding means of a pair for operating the 25 pair of retarding means simultaneously.

5. The combination of a pair of cylinders, a brake band for each cylinder, a lever connected with each of said brake bands for operating them, a cylinder and piston, the 30 piston being connected with one of said

cylinders and the cylinder with the other, said levers constituting the sole support for said cylinder and piston, yielding means for holding the piston in one position, and means whereby air can be admitted into the 35 cylinder for moving the cylinder and piston apart and simultaneously operating both brake band levers.

6. In a braking device, the combination of a pair of hubs, a separate brake for each 40 hub, a separate lever connected with each of said brakes for operating them, a cylinder and piston, the piston being connected with one of said brakes, and the cylinder independently connected with the other, means 45 whereby air can be admitted into the cylinder for forcing the cylinder and piston apart to apply the brakes to the two hubs, and means for automatically forcing the piston into the cylinder when the air pressure is released to release the brakes.

In testimony whereof we have hereunto set our hands, in the presence of two subscribing witnesses.

HENRY A. WISE WOOD.
CONRAD NORDFORS.
